UNITED STATES PATENT OFFICE

CHARLES E. CONSTABLE, OF CINCINNATI, OHIO, ASSIGNOR TO THE NATIONAL MARKING MACHINE COMPANY, OF CINCINNATI, OHIO, A CORPORATION OF OHIO

BAG HOLDER

Application filed July 30, 1928. Serial No. 296,270.

The object of my invention is to provide a bag holder of simple, durable and inexpensive construction, so constructed and arranged that bags may be easily and quickly applied thereto without injuring or destroying the bags, and at the same time adapted to support the bag in a rigid manner with a maximum opening.

A further object is to provide a bag holder adapted to fit bags of various diameters and to support the bag in an upright position with its upper and open end in a rectangular form to permit articles to be easily placed therein.

A further object is to provide a bag holder particularly adapted to support woven bags in an upright position with their open ends uppermost, and to rigidly hold the bags in an open position without the use of lugs or clamp devices.

20 A further object is to provide a bag holder particularly adapted to support bags of woven formation, such as used in laundry work, which may be easily and quickly applied to an assorting table or the like.

25 My invention consists in the construction, arrangement and combination of the various parts of the device, whereby the objects contemplated are attained, as hereinafter more fully set forth, pointed out in my claims, 30 and illustrated in the accompanying drawings, in which:

Figure 1 is a plan view of my improved bag holder.

Figure 2 is a side elevation of the same, a 35 portion of the supporting table or member for the bag holder being shown in section.

Figure 3 is a detail sectional view taken on the line 3—3 of Figure 1.

The numeral 10 indicates a table or support having an angle iron frame 11 and a bottom member 12. The table 10 is provided with supporting legs 13. Secured to the under surface of the angle irons 11, and the bottom 12, is a frame 14 formed of an angle iron 40 having parallel members 15 and a cross member 16. The horizontal flanges of the members 15 are bolted to the under surface of the angle irons 11 and the bottom 12.

The cross member 16 is spaced from the 50 member 11 a considerable distance, so that

an opening 17 is provided between the members 15 and the members 11 and 16. The dimensions of said opening are greater than the diameter of the bag to be supported therein.

The members 15 are provided with downwardly extending flanges 18, while the member 16 is provided with a downwardly extending flange 19. The flange 19 is provided with openings 20.

For supporting one side of an open end of a bag, I have provided a rod 21 supported horizontally above the member 16 and of a length slightly greater than the member 16, and having its ends provided with downwardly and inwardly projecting portions 22. The lower ends of the portions 22 terminate in outwardly and horizontally extending screw threaded portions 23. Said portions 23 are each provided with a nut 24 projecting through the openings 20. A nut 25 is then placed on the outer ends of the members 23 for locking the rod 21 in position.

Under the horizontal flange of each of the members 15 and under the members 11 and 12, I have provided a cylindrical casing 26. Said casings 26 are secured in position by means of U-bolts 27 projecting upwardly through the flanges of the members 15. A bushing 28 is threaded in the outer end of each of the members 26.

A bag supporting rod 29 is supported horizontally above the members 15 and parallel with the members 11 and 21. Said member 29 is of a length substantially equal to the length of the member 21 and has its free ends provided with downwardly extending portions 30 which extend through slots 31 in the horizontal flanges of the member 15. The lower ends of the members 30 are then bent outwardly into horizontally extending portions 32 which extend through the bushings 28 into the casings 26. The ends of the members 32 are provided with guides 33 slidably mounted in the casings 26.

Supported on each of the members 32 between the guides 33 and the bushing 28 is an expandible spring 34. This provides means whereby the member 29 is slidably mounted to move toward and from the mem-

ber 21. The springs 32 provides means for yieldably supporting the members 29 outwardly from the member 21.

When applying a bag to my device, the open end of the bag is pushed upwardly through the opening 17 between the members 21 and 29. One end of the bag is lapped over the member 21, after which the member 29 is grasped and pulled inwardly toward the member 21, and the opposite edge of the bag is lapped over the member 29, in the manner illustrated in Figures 1 and 2. The member 29 is then released and the springs 34 will draw the member 29 outwardly and cause the upper end of the bag to assume a substantially rectangular formation, with the upper edges of the bag lapped downwardly over the members 21 and 29 a considerable distance.

It will readily be seen that the top and open end of the bag is of rectangular formation with the outer edges of the upper end of the bag provided with upwardly and outwardly flaring portions.

The device is adapted to support that type of bags made of coarsely woven material or netting. Bags of this type have a certain amount of elasticity and for that reason it will be seen that, on account of the members 22 projecting inwardly and downwardly and the members 30 projecting outwardly from the frame member 11, the free edge of the bag will assume a smaller circumference than that portion which rests on top edges of the members 21 and 29, due to the elasticity of the bag.

For this reason a considerable amount of power will be necessary to pull the bag downwardly after it has once been placed in the holder, as the contracted free edge of the bag would have to be stretched and pulled over the outwardly flaring members 22 and 30.

Thus it will be seen that I have provided a bag holder of simple, durable and inexpensive construction, which may be easily and quickly applied to a supporting table, such as an assorting table used in laundries and the like, and when so supported is especially adapted to receive and hold the bags formed of elastic material, such as netting. Said holder is adapted to receive bags which vary considerably in diameter.

I claim as my invention:

1. A bag holder comprising a horizontal open frame, a fixed bag supporting rod supported horizontally above one side of said frame, having its ends bent inwardly and downwardly and thence horizontally and outwardly and anchored in said frame member, a second bag supporting member supported parallel with the first member having its free ends bent downwardly and toward the first bag supporting member, and then bent horizontally and away from the fixed

bag supporting rod, means for slidably mounting said horizontal portions to permit the second bag supporting member to move toward and from the first bag supporting member, a bag to be supported between the horizontal members, and means for yieldably supporting said second bag supporting member outwardly from the first bag supporting member.

2. A bag holder comprising a substantially U-shaped horizontally arranged frame member having horizontal and vertical flanges, the horizontal flanges of the parallel members of said frame being provided with longitudinal slots, a bag supporting rod mounted horizontally above the cross member of said frame, the end of said rod being bent downwardly and inwardly, and thence outwardly and horizontally, and anchored in the vertical flange of said cross member, a second bag supporting rod parallel with the first rod and spaced therefrom, having its free ends bent downwardly and toward the first bag supporting rod and projecting through said slots, and thence bent outwardly and horizontally, means for slidably mounting said horizontally and outwardly extending portions, and means for yieldably moving said second bag supporting rod outwardly from the first bag supporting rod.

Des Moines, Iowa, July 12, 1928.
